UNITED STATES PATENT OFFICE.

WALTER H. STEWART, OF FRANKLIN, NEW HAMPSHIRE.

CIRCULAR-KNITTING MACHINE.

SPECIFICATION forming part of Letters Patent No. 397,444, dated February 5, 1889.

Application filed November 14, 1887. Serial No. 255,113. (No model.)

To all whom it may concern:

Be it known that I, WALTER H. STEWART, of Franklin, in the county of Merrimack and State of New Hampshire, have invented certain new and useful Improvements in Circular-Knitting Machines, of which the following is a specification.

My invention relates to circular-knitting machines adapted for knitting complete seamless stockings, the heels and toes being of the "round" or "bulge" character and formed by first throwing out of action substantially one-half of the needles employed in knitting the tubular leg and foot portions of the stocking, permitting such retired needles to retain the stitches last formed thereon, and then by reciprocating the cam-plate or cylinder and gradually retiring needles at the ends of such reciprocating movements and permitting the retired needles to hold their last-formed stitches knitting a triangular or quarter-spherical web, and by continuing the reciprocating movements of the needle-operating means and gradually bringing into operation retired needles knitting another quarter-spherical web, the two webs so formed comprising a round heel or toe.

It is the object of my invention to provide improved means whereby the needles employed in knitting heels and toes, as aforesaid, may be automatically retired and brought into action in proper order.

My improvements have been wrought on that class of circular machines in which the needles are arranged and operated horizontally with the hooks toward the axis of the rotary cam-plate and the tails of the needles extending outward radially from said axis, in contradistinction to circular machines employing vertically-arranged needles.

My invention will first be described in connection with the accompanying drawings, and subsequently set forth in the claims hereunto appended.

Of the drawings, Figure 1 represents a top plan view of a machine embodying my invention, the yarn and yarn-guides being for the sake of clearness omitted. Fig. 2 represents a side elevation of the same. Fig. 3 represents a sectional detail view through the cam-plate and its attached needle-operating cams and the needle-bed and its equipments, show-

ing what I term the "long" needles and the means for controlling the position of the same to render them operative or inoperative. Fig. 4 represents a sectional detail view similar to Fig. 3, but through a portion of the machine at which the "short" needles are located. Fig. 5 represents a side view, a part being broken out, of one of the grooved slides for engaging the tails of the long needles and drawing the latter down so that they cannot be acted upon by the needle-operating cams, and shows a portion also of the chain attached to said slide. Fig. 6 is a detail view illustrating the manner of operating the chain connected with the slide mentioned in the description of Fig. 5. Fig. 6^a is a plan view of the pawl connected with the block on the end of the chain, and hereinafter more particularly referred to. Fig. 7 is an under side view of a portion of the cam-plate and needle-operating cams secured thereto.

Similar letters and figures of reference indicate similar parts in all of the views.

In the drawings, Z designates the base of the frame; W, the bed of the machine; X, pillars supporting the bed from the base; R, the needle-bed, and A the rotary cam-plate. The needles *a b* are arranged horizontally in grooves of the needle-bed R, which grooves are formed on lines extending radially from the axis of the cam-plate A. The needles lettered *a* are longer than those designated by *b*, and the former are provided with tails *c*, extending outwardly from their heels *d*, all of the needles being arranged with their hooks toward the center of the machine or axis of the cam-plate.

The grooves in which the long needles *a* are placed are deeper at their rear or outer ends than at their forward or inner ends, the depth of such grooves gradually increasing from front to rear, as shown in Fig. 3, for a purpose to be presently explained. The grooves in which the needles *b* operate are of uniform depth.

The cam-plate A is provided at a proper point on its under side with needle-operating cams 15 16 Q 17, the space *e* between the cams 15 16 forming a path for the passage of the heels of the short needles *b*, and the space *f* between cams 15 and 16 forming a path for the heels of the long needles *a*, the hooks of

both sets of needles being on the same line concentric with the axis of the cam-plate A, while the distance between the heels of the long needles *a* and short needles *b* corresponds 5 to the distance between the two cam-paths *e* and *f*. The needles are projected and retracted by the cams 15 16 Q 17 in a manner which will be readily understood by those skilled in the art without further description 10 herein.

11 designate sinkers arranged to operate in slots or grooves formed in a ring, 21, attached to the inner edge of the bed-plate R, one such sinker being placed between each two needles 15 and moved up and down by a cam, 19, secured to a ring, 20, turning with the cam-plate A. Cam 19 operates in a notch, 80, formed in the rear edge of the sinkers, and is so constructed and timed in its movements as to raise the 20 sinkers as the needles are retracted to form a stitch, allowing the yarn or loop to be drawn under the hook *g* of the sinker, and when said sinker is depressed the hook *g* operates to hold back the loop on the needle as the latter 25 is projected to take yarn for a new stitch.

The cam-plate A has gear-teeth *h* formed on its outer edge, which teeth mesh with the teeth of a small bevel gear-wheel, B, the latter being made fast to an arbor, C, adapted 30 to turn in bearings formed in a bracket, 5, attached to the bed of the machine. Turning loosely on arbor C are pulleys D E, and between the pulleys D E, secured to arbor C by a spline and groove, (not shown,) is a clutch-collar, F, the manner of securing said clutch-collar to said shaft being such as to permit the former to be turned with the latter and yet be moved longitudinally thereon. Both 35 ends of the clutch-collar F may have clutch-teeth formed thereon and adapted to engage similar teeth formed on the pulleys D E, as is common in the construction of clutches; or the ends of the collar may be made tapering in form, as shown in dotted lines in Fig. 2, 40 which tapering ends may be made to fit into corresponding recesses in the adjacent sides of the pulleys D E. Pulleys D and E are in the operation of the machine driven in opposite directions, as will presently be explained, 45 and clutch-collar F is so constructed that when its tapering end adjacent to pulley D is forced in the recess in the side of said pulley the friction between the two parts will carry 50 said clutch-collar and arbor C around in one direction, and when said clutch-collar is moved into contact with pulley E the arbor will be rotated in the opposite direction.

The description of the machine thus far given is believed to be sufficiently full to enable 55 knitting artisans to understand that it can readily be equipped with yarn-guides of any suitable or common construction and be operated to produce a tubular knit web—such as is employed in the leg and foot portions of 60 stockings—the cam-plate A being rotated for that purpose. When, however, the heel or toe portion of a stocking is to be formed and said

heel or toe portion is to be given a round or hemispherical shape, the first step in the operation is to render a portion of the needles used in knitting the tubular web inactive or inoperative, permitting them to retain the stitches or loops last formed thereon. As my machine is organized the short needles *b* are rendered inoperative for the purpose mentioned, and this is accomplished by raising the cam Q, so that it will not act upon the heels of needles *b* to project the same. 70

Cam Q is secured to a block, N, pivoted at its forward end on a pin, P, to the cam-plate A, or to a block, O, set into the cam-plate. A recess is formed in the cam-plate above cam Q and block N, so as to permit said block and cam to be swung upward and carry the cam out of engagement with the heels of the short needles, a pin, M, extending up through a slot in cam-plate A, as seen in Fig. 3, permitting this to be done, and to render inoperative the short needles *b*. The cam Q may be held in raised position by the frictional engagement 85 of its sides or edges with the sides of the recess into which it is raised, or by other suitable means, this feature of the construction forming no part of my claimed improvement.

With the needles *b* rendered inactive, the cam-plate A may be reciprocated to knit heel and toe work, and this reciprocation of said cam-plate is accomplished by placing a pin, L, in a hole in the cam-plate, as shown in Fig. 1, said pin extending above the upper 90 surface of said cam-plate just far enough to strike the lever K, secured to an arbor, I, having a bearing in a suitable sleeve, J, secured to the bracket 5, to which arbor I is also secured one end of a lever, G, the other end of 95 which is provided with a pin, *i*, extending down into a groove, II, formed in the clutch-collar F. With this construction it will be seen that as the cam-plate is rotated in one direction and pin L is brought in contact with 100 and moves lever K said lever will be so operated as to cause its connected parts to move clutch-collar F out of contact with one of the pulleys D or E and into engagement with the other, and so cause cam-plate A to be rotated in the opposite direction until pin L 105 again comes in contact with lever K, when the former movement of the cam-plate will be effected, and so on as long as pin L is in position in the cam-plate. 110

The short needles *b* may be supposed to be arranged in the grooves in the needle-bed between the points 22 22, Fig. 1, the remainder of the needles being long needles *a*. In a groove or way, 23, in the rear of the short needles are arranged two segmental slides, T T, arranged side by side and adapted to be moved in opposite directions in way 23 around the cam-plate, said way 23 being formed between the rear edge of the needle-bed and a 125 rim or rib, 32, on the bed-plate W, as is clearly shown in Figs. 3 and 4. To the end of each slide in the direction in which it is to be moved from the points 22 is secured one end 130

of a chain, S, also adapted to move in the bottom of the way 23 and form a rest for the tails c of the long needles a, so that the heels of said needles will be engaged and operated by the cams 15 16. The form of slide T and chain S is represented in Fig. 5, a portion of the slide being pictured as broken out. Said chains S extend around in way 23 to and around rollers 6 6 (shown in full and dotted lines in Fig. 1) and into a groove or way formed in brackets 7 7, attached at their inner ends to the bed of the machine. At their said free ends the chains S S are each provided with a block, 8, as shown in detail in Fig. 6, to which block is pivoted the double-armed pawl 9, the arms of which pawl are adapted, one at a time, to be engaged by the teeth of a rack-bar, 10, arranged to be reciprocated in brackets 7 above chain S, block 8, and its attached pawl 9, one such rack-bar being provided for each bracket 7. With this construction and arrangement of parts it will be seen that slides T, chains S, and blocks 8 may be moved in one direction or the other in ways 23 or brackets 7 by reciprocating the rack-bars 10, the direction in which each of said chains and its adjuncts are moved being dependent upon which arm of pawl 9 is in engagement with the teeth of its co-operative rack-bar.

A spring, r, Fig. 6, is adapted to act against one or the other of the inclined surfaces formed on the under side of the pawl 9, and serves to hold either arm, as may be desired, of said pawl in position to engage the teeth of rack-bar 10. The opposite ends, t' t'', of the pawl-arms are offset each from the other, as shown in Fig. 6^a, so as that when the chain is, for example, moved outward in the bracket the end t'', then in engagement with the teeth of the rack-bar, may strike a lug or dog, f^b, on one side of the outer end of the bracket, and so disengage said end t'' of the pawl from the teeth of the rack-bar, at the same time throwing the opposite end, t', of the pawl into engagement with said teeth, and when the chain is moved in a lug similar to lug f^b on the opposite side of the inner end of the bracket will strike the end t' of the pawl and return it to its first-mentioned position.

As the slides T are moved from the points 22 in the direction of the arrows in Fig. 1, the tails c of the needles a will enter the slots 25 in said slides and be drawn down, so as to carry the heels of said needles below and out of engagement with the needle-operating cams 15 16 and so throw said needles out of action, and when said slides are moved in a direction opposite to the arrows in Fig. 1 the tails of said long needles will ride up out of said groove 25 onto chain S and so be brought into operative position.

The advantages arising from the use of the chain in connection with the slides are that the chain which supports certain of the needles in their normal position may in the narrowing and widening operation be moved en-

tirely out of the way of the needles and needle-supports, so that the needle-withdrawing features of the slides may be brought very near together to form the point of the heel, and so that more than half the needles of the circle may be employed, if desired, in knitting the heel. This cannot be done in machines where a portion of the slide is employed to hold certain of the needles in their normal position and another portion employed to raise certain needles into operative position, since if an attempt should be made to throw more than half the needles out of operation the part of one slide constructed to hold the needles in operative position would come in contact with and raise the needles first lowered by the other slide after more than one-quarter of the number of needles have been lowered by each slide.

The teeth in the rack-bars 10 are formed at such distance apart that by reciprocating said bars the distance between two teeth will be just sufficient to cause the slide T operated thereby to throw out or bring into action a needle, a, and by this means control the long needles to perform the operation of widening and narrowing to knit heel and toe work by a process so well understood by knitting artisans as to not require elaboration herein.

The reciprocation of rack-bars 10 in brackets 7 is effected by means of a lever, 30, secured at its center on a stud, 12, having a bearing in a bar secured to brackets 7, said lever 30 being pivotally connected at its ends with the rack-bars 10. The upper end of stud 12 is connected to the rear or outer end of a two-armed lever, 13, the arms of which lever extend out over the cam-plate A of the machine and are adapted to be struck and moved from side to side in the reciprocating movements of said cam-plate by a pin, 14, placed in a hole in said cam-plate, said pin 14 being placed near enough to the axis of the cam-plate to pass the end of lever K without affecting the position of said lever, and two-armed lever 13 being arranged at a plane sufficiently high to permit pin L to pass thereunder without moving the last-mentioned lever.

In the movement of lever 13 from side to side, as indicated by the dotted lines in Fig. 1, by the reciprocating movements of the cam-plate and the action on said lever 13 by pin 14 rack-bars 10 will be reciprocated the distance between any two teeth of said rack-bar, and so raise a needle into or withdraw one from action, the direction in which the chains S and their attached slides T are moved depending upon the adjustment of pawl 9—that is, as to which arm of said pawl is made to engage with the teeth of the rack-bar, as will be understood without further explanation.

A bracket, 1, is attached to the bed of the machine and supports suitable bearings for the main arbor 26, having a driving-pulley, 4, secured upon its outer end and carrying pulleys 2 3. A crossed belt, 37, connects pulley

3 with pulley E, and straight belt 38 connects pulley 2 with pulley D, this arrangement serving to effect the rotation of pulleys D and E in opposite directions.

5 In knitting a stocking the machine will be set to effect the knitting of a tubular web by the rotation of the cam-plate A and be operated until a sufficient length of such web has been produced, when the pins L 14 will be 10 placed in the cam-plate and pawl 9 adjusted so as to effect the movement of chains S outward in brackets 7 7, when the cam-plate will be given a reciprocating motion, and the slides T T will be drawn around step by step 15 toward the rollers 6 6, drawing the long needles down one by one out of position to be operated by the cams 15 and 16 until the web being knit is narrowed to the desired extent, when the pawls 9 will be so adjusted as to 20 move the chains S and slides T back to their former position, gradually bringing into operation the needles thrown out of action and completing the formation of a hemispherical or bulge piece suitable for a heel. The pins 25 L 14 are then removed from the cam-plate, when circular knitting will be performed again to form a tubular web for the foot portion of the stocking, and the machine will be operated substantially as has been described 30 with reference to the formation of the heel for knitting the toe portion.

It is obvious that changes may be made in the form and arrangement of parts constituting my invention without departing from the 35 nature or spirit of the improvement.

What I claim is—

1. A rotary cam-plate, a needle-bed, two sets of needles, *a b*, the former set provided with extensions or tails, a movable chain supported 40 by the bed and adapted to form a support for the tails of said needles, means for moving the chain, a grooved or slotted slide attached to the said chain to engage the tails of said needles to lower or depress the same, and a bracket 45 provided with a support or way upon which said chain may be moved and by which it may be guided from the bed, combined and arranged substantially as hereinbefore set forth.

2. The combination, with the rotary cam-

50 plate, the grooved needle-bed, and two sets of needles, *a b*, the former needles provided with tails *c*, of chains S and attached grooved slides T, supported and movable in ways in the bed, said slides being adapted to engage

the tails of said needles *a* to raise and lower 55 the same in their grooves in the bed, ways or brackets 7, in which said chains are adapted to move, rack-bars movable in and guided by said brackets, a two-armed pawl on each of said chains adapted to be engaged by said 60 rack-bars, and means for reciprocating said rack-bars, as set forth.

3. The combination, with the needle-bed, the needles *a b*, slides T, and attached chains S, bearing the two-armed pawls 9, of brackets 65 7, rack-bars 10, lever 30, pivoted at its ends to said rack-bars, two-armed lever 13, connected with the fulcrum of said lever 30, and the rotary cam-plate provided with the pin 14, as set forth. 70

4. The combination, with the needle-bed, needles, and rotary cam-plate, of a rotary arbor, C, a gear connecting said arbor with said cam-plate, pulleys D E, loose on said arbor, clutch-collar F, splined on said arbor to be 75 moved longitudinally thereon, but to rotate therewith, levers G K and their fulcrum-pin I, and pin L, removably secured to the cam-plate, as set forth.

5. The combination, with the needles *a*, provided with the tails *c*, of the rotary cam-plate, the needle-bed provided with grooves in which said needles operate, said grooves being deeper at their outer or rear than their inner or forward ends, chain S, on which the tails of said 85 needles are adapted to rest, slide T, provided with a groove, 25, adapted to engage the tails of said needles, said slide being attached to said chain, a bracket provided with a support or way upon which said chain may be moved 90 and by which it may be guided from the bed, and means for moving said chain, as set forth.

6. The combination, with the rotary cam-plate, needle-bed, needles, slide T, and chain S, of the roller 6 on the needle-bed, block 8, 95 and two-armed pawls 9, attached to the chain, bracket 7, reciprocating rack-bar 10, and means for reciprocating said rack-bar, as set forth.

In testimony whereof I have signed my name 100 to this specification, in the presence of two subscribing witnesses, this 24th day of October, A. D. 1887.

WALTER H. STEWART.
